COOLING UNIT FOR REFRIGERATING APPARATUS

Application filed March 11, 1929. Serial No. 346,205.

This invention relates generally to flooded type cooling units of compressor type refrigerating apparatus, particularly to those in which fluids soluble with oil are used as the refrigerant, and consists of certain novel features of construction, combinations and arrangements of parts that will be hereinafter more fully described and particularly pointed out in the appended claim.

Ordinarily a certain amount of oil used as lubricating means for the compressor of a refrigerating apparatus finds its way around the piston or pistons of the compressor and into the refrigerating conduits of the apparatus. In the past such escaping oil has been carried along with the refrigerant into the flooded type cooling units, and when the refrigerant, such as methyl chloride, is soluble with the oil, such oil was trapped in the cooling unit as the refrigerant of the mixture therein evaporated. Consequently the oil did not return to the compressor to lubricate the same and such accumulation of oil in the cooling unit depleted materially the lubricating means for the compressor and prevented such compressor from getting the proper lubrication.

When a refrigerant such as SO_2 that is not soluble with oil is used, the oil floats on top of the refrigerant and may be carried off satisfactorily and returned to the compressor, however in the past, so far as I am aware, no satisfactory means has been devised for returning to the compressor oil that has commingled with a refrigerant such as methyl chloride that is soluble with the oil.

Therefore, it is an object of the present invention to provide means, preferably associated with the cooling unit, for returning to the compressor the lubricating oil that has escaped from the compressor and mixed with the refrigerant, so that the compressor will be properly lubricated.

With the present invention this is preferably accomplished by utilizing the velocity of the refrigerating gases resulting from evaporation of the liquid refrigerant in the unit to withdraw a mixture rich in oil from the first mentioned mixture in the cooling unit and return it to the compressor.

It is also an object of the present invention to utilize a portion of the return conduit as a vaporizing chamber to permit the liquid refrigerant of the mixture rich with oil to evaporate in the cooling unit before passing therefrom to the compressor, and thereby aid the unit in its cooling and refrigerating work.

In the accompanying drawing:—

Figure 1 is a diagrammatic view of a portion of a refrigerating apparatus and showing a cooling unit and associated means embodying my invention, and

Figure 2 is a view of a slight modification.

Referring now to the drawing,—1 is a cooling unit adapted to receive liquid refrigerant such as methyl chloride from a suitable container (not shown) and adapted to be mounted in a suitable freezing chamber of a refrigerator cabinet and the like. Usually the supply of refrigerant from the container to the unit such as 1 is regulated by a float chamber or capillary tube and in the present instance 2 may be either a float chamber or capillary tube and is connected by a suitable conduit 3 to and adapted to regulate the supply of the refrigerant to the cooling unit 1. 4 designates the usual level of the refrigerant in the unit, 5 is the return line or conduit for returning to the compressor (not shown) the refrigerant gases developed by evaporation of liquid refrigerant in the unit 1 and having a coil 6 in the unit above the liquid level 4 terminating in a depending flared portion 7, and 8 is a substantially vertical tube having a restricted passage and suitably supported from and in substantially parallel relation to an upright side wall of the unit 1, preferably with the lower end 9 thereof spaced above the bottom wall 10 of the unit and with the upper end 11 thereof in the flared portion 7 of the return conduit 5. Thus the construction and arrangement of the flared portion 7 and tube 8 is such that a Venturi or ejector type suction device is provided for withdrawing the contents of the tube 8 into the return conduit 5.

In use since a refrigerant such as methyl chloride soluble with oil is used as the refrigerant, and since oil used for lubricating the

compressor escapes from the compressor into the refrigerant lines, the contents of the unit 1 is a mixture of the methyl chloride and lubricating oil. As usual the liquid refrigerant of this mixture evaporates, but in the present instance gases resulting from this evaporation are received in the flared portion 7 of the conduit 5, and the velocity of such gases passing through this flared portion is utilized to withdraw a mixture richer with oil from the unit at the bottom thereof through the tube 8 into the conduit 5 so that oil escaped from the compressor and finding its way into the refrigerant lines such as 3 will be returned to the compressor, and the said compressor will be properly lubricated. In fact, the mixture drawn upwardly in the tube 8 is decidedly richer with oil than that discharged from the conduit 3 into the unit.

In this connection the size of the passage in the tube 8 may be proportioned relative to the size of the passage in the conduit 3 so that the quantity of oil removed from the unit 1 will be substantially equal to that received by it. In any event oil is constantly withdrawn from the unit and is returned to the compressor so that it is properly lubricated.

The coil 6 provided in the unit 1 above the flared portion 7 is very important since it permits the refrigerant of the mixture withdrawn from the tube 8 to evaporate in the unit 1 and thereby aid in the cooling and refrigerating of the unit.

In Figure 2 I have shown a slight modification in which the upper end 11 of the tube 8 is received in the throat 12 of a venturi 13 that may be connected at 14 by any suitable means to an end of the coil 6 or directly to a portion of the conduit 5 as may be desired.

While it is believed that from the foregoing description the nature and advantages of the invention will be readily apparent, I desire to have it understood that I do not limit myself to what is herein shown and described and that such changes may be resorted to when desired as fall within the scope of what is claimed.

What I claim as my invention is:

In a refrigerating apparatus, a tank constituting a cooling unit and containing a mixture of lubricating oil and refrigerant soluble with said oil, the level of the mixture being such that space is provided in the tank at the top thereof for the evaporation of the refrigerant, a conduit having a coil substantially horizontally disposed within the tank and terminating above said liquid level in a depending flared portion that is adapted to receive the refrigerant gases resulting from evaporation, and a substantially vertical tube partly submerged in the liquid mixture in substantially vertical alignment with said depending portion, having its lower end spaced slightly above the bottom of the tank and having its upper end above the level of

the liquid mixture in spaced relation and terminating substantially within the depending flared portion aforesaid, whereby the refrigerant gases resulting from evaporation of liquid refrigerant in said tank may pass upwardly around the upper end of said tube into said depending flared portion, and the velocity of said gases at this point may be utilized to draw upwardly in said tubing and thence into said flared portion a mixture of liquid refrigerant and oil rich with the latter.

In testimony whereof I affix my signature.
HAROLD A. GREENWALD.
